[57] CLAIM

The ornamental design for a casing for electrical equipment, or the like substantially as shown and described.

DESCRIPTION

FIG. 1 is a front elevational view of a casing for electrical equipment showing my new design;

FIG. 2 is a left side elevational view thereof, the right side being a mirror image;

FIG. 3 is a rear elevational view thereof;

FIG. 4 is a top plan view thereof;

FIG. 5 is a perspective view thereof;

FIG. 6 is a front elevational view of a second embodiment of a casing for electrical equipment;

FIG. 7 is a left side elevational view thereof, the right side being a mirror image;

FIG. 8 is a rear elevational view thereof;

FIG. 9 is a top plan view thereof, and

FIG. 10 is a perspective view thereof.
